(57) **CLAIM**

The ornamental design for a lighting fixture, as shown and described.

DESCRIPTION

This application is related to a design patent application naming the same inventors, entitled "Lighting Fixture," filed on the same date and given 29/420,705. The contents of that application are incorporated by reference herein in their entirety.

FIG. 1 is a perspective view of a lighting fixture illustrating our new design;

FIG. 2 is a front elevational view of the lighting fixture;

FIG. 3 is a rear elevational view of the lighting fixture;

FIG. 4 is a side elevational view of one side of the lighting fixture;

FIG. 5 is a side elevational view of the other side of the lighting fixture;

FIG. 6 is a top plan view of the lighting fixture; and,

FIG. 7 is a bottom plan view of the lighting fixture.

In the drawing figures, the broken lines immediately adjacent the shaded areas represent the bounds of the claimed design, while all other broken lines are directed to environment and are for illustrative purposes only; the broken lines form no part of the claimed design.

1 Claim, 5 Drawing Sheets
